BENDING MACHINE

Gustav A. Hoener, Detroit, Mich.

Application December 8, 1932, Serial No. 646,274

25 Claims. (Cl. 153—40)

My invention relates to improvements in bending machines in which the member to be bent or formed is pulled from a locating member during the bending or forming operation; and the objects of my improvement are, first, to provide a bending machine in which the member is bent or formed with a plurality of bends extending in different planes in one operation; second, to provide a bending machine for bending any kind 10 of metal tubing of round, square, oval, or similar shape as well as various kinds of moldings or similar members; third, to provide a bending machine which accomplishes a bending operation as it pulls the member to be bent from an arbor; 15 fourth, to provide a bending machine having an arbor with a portion fitting within the object to be bent; fifth, to provide a bending machine having pressure members engaging the outside of the member to be bent at points adjacent a 20 member within the member for absorbing the thrust load developed during the bending operation; sixth, to provide a bending machine having a revolving fixture plate; seventh, to provide a bending machine having a revolving fixture plate 25 of irregular outline with teeth members around its irregular periphery; eighth, to provide a bending machine having a revolving fixture plate operated by an elastic drive means; ninth, to provide a bending machine having a pair of flexibly mounted pressure rollers for developing bending 30 pressures; tenth, to provide a bending machine having a revolving fixture plate provided with a plurality of fixture members for supporting a plurality of members to be bent; eleventh, 35 to provide a bending machine having a fixture plate provided with a rim portion of uniform width for engaging driving and stabilizing members; twelfth, to provide a bending machine having a fixture plate adapted to travel alternately 40 in straight lines and then along a radial path; thirteenth, to provide a bending machine having a flexible means for driving a fixture plate together with means for maintaining the flexible drive means in a taut position adjacent the 45 fixture plate; fourteenth, to provide a bending machine having a fixture member adapted to pass with the member to be bent, between a pair of pressure rollers; fifteenth, to provide a bending 50 machine having a fixture member constructed with flexible mounted sections; sixteenth, to provide a bending machine having a fixture plate adapted to move in a single plane and having portions adapted to be deflected from the plane of movement of the fixture plate; and seven- 55 teenth, to provide a bending machine having a

pressure member rotatably mounted on a pivotally mounted member.

I attain these objects by mechanism illustrated in the accompanying drawings, in which—

Figure 1 is a plan view of the bending machine, disclosing a horizontal section on the line 1—1, Fig. 4; Fig. 2, a vertical section of a part of the bending machine on the line 2—2, Fig. 1; Fig. 3, a vertical section of a part of the bending machine on the line 3—3, Fig. 1; Fig. 4, a vertical section of the bending machine on the line 4—4, Fig. 1; Fig. 5, a partial horizontal section through the pressure rollers disclosing a pipe having a portion which has passed through said pressure rollers and has been bent or formed 60 to a pre-determined shape; Fig. 6, a partial vertical section on the line 6—6, Fig. 5; and Fig. 7, a vertical section on the line 7—7, Fig. 4.

Similar numerals refer to similar parts throughout the several views.

The base portions 1 of the bending machine are supported on the floor 2 and the table or housing 3 is suitably secured to and supported on the flanges 62 of the base portions.

The housing 4 is suitably secured to the table 3 by the flange 5 and the bolts 6, the housing 4 being provided with the flange 7 which fits over the edge of the table 3 to relieve the bolts 6 from carrying the total weight of the housing 4. The housing 4 is provided with the boss 8 to which 80 is secured the flange 9 of the electric motor 10, the flange 9 being secured to the boss 8 by the bolts 11. The electric motor 10 is provided with and operates the shaft 12 to which is suitably secured the worm 13 which engages and operates the worm gear 14 which is secured to the shaft 15 by the key 16. The shaft 15 is rotatably mounted in the boss 17 of the table 3. The gear 18 is secured to the shaft 15 by the key 19 and is adapted to rotate with the shaft 15 and the worm gear 14. 95

The worm gear 14 and the gear 18 are also secured on the shaft 15 by the nut 20 and key 19 and the washer 21 which hold the worm gear 14, the gear 18, and the shaft 15 in their proper operative positions with the worm gear 14 and the shoulder 22 of the shaft 15 respectively held against the end surface of the boss 15 and the upper surface 23 of the table 1.

The gear 24 is secured to the shaft 25 by the key 26, the shaft 25 extending through and being 105 rotatably mounted in the boss 26. The sprocket 27 is also secured to the shaft 25 by the key 28, the gear 24 and the sprocket 27 being secured in their proper operative positions by the nut 29 and the washer 30 holding the gear 24 against the 110

end surface of the boss 26 and the sprocket 27 between the upper surface 23 of the table 1 and the shoulder 31 of the shaft 25. The shaft 32 may be suitably secured at one end of the table 3 and the sprocket 33 is rotatably mounted thereon, the chain 34 being driven by the sprocket 27 to further drive the sprocket 33 which acts as an idler sprocket.

The shaft 32 is provided with the shoulder 35 to retain the sprocket 33 in its proper operative position relative to the upper surface 23 of the table 3.

The fixture plate or housing 36 is provided with the internal surface 37 which is adapted to engage the roller 38, as hereinafter disclosed, the fixture plate 36 being provided with the sprocket teeth 39 around its periphery, said sprocket teeth 39 being engaged by the chain 34 which thus causes the fixture plate 36 to travel past the roller 38, the fixture plate 36 thus being actuated to follow a line of movement which is determined by the shape or outline of the fixture plate 36, the fixture plate 36 thus alternately traveling in straight lines and then revolving about the center of the roller 38 as the irregular shaped portions, such as the corners of the fixture plate 36, take their positions adjacent the roller 38, the irregular outline or shape of the fixture plate 36 being determined by the desired shape of the object to be bent or formed.

It is to be noted that the width of the rim portion 40, of the fixture plate 36, between the pitch line of the sprocket teeth 39 and the surface 37, will be maintained the same throughout the length of said rim portion 40.

It is also to be noted that the sprocket teeth 39, of the fixture plate 36, will form sprocket rack portions on the straight sides and portions of sprocket gear portions at the corners of the fixture plate 36, the actual outline or shape of the fixture plate 36 and its sprocket teeth portions being possible of construction to meet any desired variations of the fixture plate disclosed as may be required to produce any desired shape or form of an object to be bent or formed.

The rim portion 40 is provided with recesses 41 for retaining the rollers 42 which thus provide anti-friction bearing members between the fixture plate 36 and the surface 23 of the table 3, the proper operating space 43 being maintained between the fixture plate 36 and the surface 23 of the table 3.

The idler sprockets 64 and 44 are mounted on the levers 45, one of which is disclosed in Fig. 2, the levers 45 being adapted to oscillate on the bearing portions 46 of the studs 47 which may be threadably secured in the bosses 48 of table 3, the levers 45 being retained on the studs 47 by the shoulder portions 49 of the studs 47. The idler sprockets 64 and 44 are rotatably mounted on the shafts 50 which are secured in the levers 45 by the nut 51, the sprockets 64 and 44 being retained between the shoulder portions 52 of the shafts 50 and the lower surfaces of the levers 45. The sprockets 64 and 44 of the levers 45 will always be forced into engagement with the outside portion of the chain 34 and thus take up any slack in the chain 34 on its outside portion and maintaining its inner portion, between the sprockets 27 and 33, in a taut or tightened position to properly engage and eliminate any lost motion between the chain 34 and the sprocket teeth 39 on the fixture plate 36, the levers 45 being locked in their proper positions by screwing

the studs 47 down to the position which will hold the levers 45 in their said proper positions.

The housing 4 extends upwardly and is provided with the portion 63 which extends inwardly over the table 3, the portion 63 being provided with the chamber 53 in which is slidably mounted the head member 54, the head member 54 and the chamber 53 being of a shape as will absorb any transverse thrust load reaction developed in the bending or forming operation hereinafter described. The head member 54 is provided with the extension portion 55, which extends through the opening 56 in the lower wall of the chamber 53 of the housing 4. The extension portion 55, of the head member 54, is provided with the boss 57 in which is secured the shaft 58 by the nut 59, the pressure roller 66 being rotatably mounted on the shaft 58 between the face of the boss 57 and the shoulder portion 67 of the shaft 58. The extension portion 55 is further provided with the boss 68 in which is suitably secured the shaft 69 on which is pivotally mounted the lever 70 on which is rotatably mounted the pressure roller 71 which is suitably retained between the shouldered portions 72 and 73 of the lever 70. The lever 70 is provided with the arm 74, which is suitably secured thereto, the arm 74 being provided with the shaft 75, which is suitably secured in the arm 74 by the nut 76. The roller 77 is rotatably mounted on the shaft 75 between the face of the arm 74 and the shoulder portion 78 of the shaft 75.

The guide members 79 are constructed with the same form or outline as the rim portion 40 of the fixture plate 36 and are each provided with the surface 80 for contacting the roller 77, the guide members 79 being further provided with the brackets 81 which are fastened to the rim portion 40 of the fixture plate 36 by the screws 82.

The fixture or form members 83 are constructed of the desired shape to which the member is to be bent or formed and are arranged to extend parallel with and adjacent the guide members 79, the fixture members 83 being provided with a curved portion 84 which fits and engages with the groove 85 in the pressure roller 71.

It is to be noted that whereas my bending machine is adaptable for bending any kind of hollow or tubular members whether round, oval, square or other shape and also various kinds and shapes of mouldings and similar members in one operation, I have disclosed the machine as operating on a pipe 86 of usual construction as this will more easily and clearly disclose the operation of my invention. The pipe 86 fits between and engages the groove 87 of the pressure roller 66 and the grooves 88 of the fixture members 83.

The pipe 86 is placed or telescoped over the arbor 89 which is provided with the ball portion 90 which fits within the inside surface of the pipe 86.

The roller 38 is rotatably mounted on the shaft 91 which is suitably secured in the lever 92 by the nut 93, the roller 38 being retained between the shoulder portion 94 of the shaft 91 and the face of the lever 92. The lever 92 is pivotally mounted on a shaft 95, which is suitably secured in the table 3, the lever 92 being further connected with the shaft 96 by means of a swivelly mounted member 97 suitably secured in the lever 92, the outer end of the shaft 96 being rotatably mounted in the bracket 98 which is secured to the table 3 by the screws 99, the shaft 96 being 150

provided with the handwheel 100 for manually operating the shaft 96.

It is to be noted that the operation of the handwheel 100 will cause the lever 92 to move the roller 38 into contact with the internal surface 37 of the fixture plate 36 which will in turn force the teeth 39 into engagement with the chain 34 and at the same time the surface 80 of the guide member 79 will be forced into engagement with the roller 77. The thrust of the guide member 79 against the roller 77 will cause the lever 70 to pivotally move to force the pressure roller 71 into engagement with the curved portion 84 of the fixture member 83 which will cause the pipe 86 to be gripped between and within the groove 88 of the fixture member 83 and the groove 87 of the pressure roller 66, the pipe 86 being thus gripped at points opposite the ball portion 90 of the arbor 89, the ball portion 90 absorbing the thrust of the pressure against the outside surface of the pipe 86 during the bending or forming operation, the spherical surface of the ball portion 90 allowing the pipe 86 to bend and form to the shape or form of the fixture members 83.

It is to be noted that the above mentioned movement of the lever 92 and the roller 38 will be possible due to the formation of the slot 101 in the table 3 which will permit the shaft 91 to move within said slot 101.

It is also to be noted that the head member 54 will be actuated to a position in which the pressure roller 66 will grip the pipe 86, in conjunction with the fixture member 83, by means of the shaft 102 which is supported in and threadably engages the boss 103 of the housing 4, the inner end of the shaft 102 being connected to and supported in the member 104 which is slidably mounted in the bore 105 of the portion 63 of the housing 4, the member 104 forming a retainer member for the spring 106 which extends within the recess 107 of the head member 54, the shaft 102 being provided with the handwheel 108 for manually operating the shaft 102.

The operation of the handwheel 108 and shaft 102 will cause the member 104 to exert a force tending to compress the spring 106 and force the head member 54 to move toward the fixture member 83, the spring 106 always permitting the pressure roller 66 to free itself when necessary or to adjustably accommodate itself to the necessary positions required when bends or irregular shapes are being formed in the pipe 86.

Also the actuation of the pressure roller 66, by means of the spring 106 against the head member 54, together with the actuation of the fixture member 83, by means of the pressure roller 66 and the fixture member 83 to be separated slightly when the pipe 86 is initially entered therebetween, the pressure roller 66 and the fixture member 83 being immediately returned to positions, in which they firmly grip the pipe 86, by means of the manual operation of the roller 38.

It is to be understood that the operation of bending and forming a member to any desired shape in my bending machine is accomplished first by placing the member, which in the present disclosure, is the pipe 86, on the arbor 89 with the ball portion 90 on the inside of the pipe 86 at a point between the pressure roller 66 and the fixture member 83, this being readily accomplished by inserting the end of the pipe 86 and the ball portion 90 therein between the pressure roller 66 and the fixture member 83, the spring 106 allowing the gripping members to slightly separate, if necessary, said gripping members

immediately resuming their gripping hold on the pipe 86 which securely holds the pipe 86, and as the fixture plate 36 is actuated in its travel movement by the chain 34, the pipe 86 will be pulled from the arbor 89 and over the ball portion 90. In order to secure the arbor 89 from moving or traveling along with the pipe 86, the arbor 89 is provided with the head portion 109 which engages the jaws 110 of the table 111 which is slidably mounted on the ways 112 of the table 113 which, in turn, is slidably mounted on the ways 114 of the table 116 of the bracket 115 which is secured, by the bolts 144, to the table 3, in a manner similar to the housing 4. The arbor 89 fits between the jaws 110 of the table 111 and is easily removed for insertion within a pipe 86, the fixture plate 36 being provided with a pair or more of fixture members 83, so that the pipe 86, after bending or forming, may be removed from one of the fixture members 83 while another fixture member 83 and the pipe 86 are passing between the pressure roller 66 and a fixture member 83.

The table 113 is provided with the shaft 117 which is suitably mounted therein and adapted to engage and move the table 111 when the handwheel 118 is manually operated. The table 116 is provided with the shaft 119 which is suitably mounted therein and adapted to engage and move the table 113 when the handwheel 120 is manually operated. The position of the jaws 110 can be thus readily adjusted to accommodate various lengths of arbors and pipes and to provide the proper position of the arbor 89 and the pipe 86 relative to the fixture members 83. The fixture members 83 are provided with brackets 121 which are provided with flanges 122 by which said fixture members 83 are secured to the fixture plate 36 by the screws 123.

It is also to be noted that when it is desired to form the pipe 86 with a bend extending at an angle with the horizontally extending fixture plate 36, the fixture members 83 will be provided with the sections 124 and 125, or similar sections, which are pivotally connected to one another by the pins 120 145, the sections 124 and the adjacent portions 126 and 127 of the fixture members 83 being provided with the inclined sides 128 to permit the sections 124 to pivotally move and travel along a path or line of movement extending at an angle with the face of the fixture plate 36. The sections 124 are provided with bosses 129 which pivotally move within similar shaped recesses 130 in the sections 125 and also in the portions 126 and 127 of the fixture members 83. The sections 125 and 130 the portions 126 and 127 of the fixture members 83 are provided with the extension portions 131 which are adapted to contact with the sides of the sections 124 and prevent the pivotal movement of the sections 124 beyond a pre-determined 135 amount thus insuring that the sections 124 and 125 will never move beyond an aligned position, in one direction, parallel with the face of the fixture plate 36 and at the same time allowing the fixture members 83 to be guided to the required 140 position necessary to accommodate the desired bend or form with which the pipe 86 is to be constructed.

In order to actuate the fixture members 83 to the required position to which the pressure roller 145 66 and the fixture members 83 will bend or form the pipe 86, the portions 127 of the fixture members 83 are each provided with the arms 132 having the bosses 133 in which is suitably secured the pin or shaft 134 on which is rotatably mounted 150

the roller 135 which is suitably retained in a slot in the bosses 133, the pins 134 being provided with the shoulder portions 136 and with the cotter pins 144.

5 The guide member 137 is provided with the surface or cam portion 138 with which the roller 135 contacts, thereby causing the fixture member 83 to be displaced to the required position for the pressure roller 66 and the fixture members 83 to 10 form the desired shape of the pipe 86. The guide member 137 is provided with the flanges 139 through which extend the screws 140 for securing the guide member 137 to the fixture plate 36, the guide member 137 being located on the fixture plate 36 at the proper position so that when the roller 135 contacts therewith, the pipe 86 will be bent or formed with the required bend or form 15 located in the desired position on the pipe 86.

The electric motor 10 may be suitably connected with a source of electric current and may also be connected, by the wires 141 and the wires 142, to the switch assembly 143 suitably located at the front of the table 3 for convenience of the operator in controlling the operation of the bending 20 machine.

It is also to be understood that the bending machine may be power operated by sprocket and chain means or other elastic drive or similar driving means.

30 I claim:

1. In a machine for bending a pipe, the combination of a supporting base provided with a table, a fixture plate movably mounted on the table of said supporting base, said fixture plate being provided with a rim portion having tooth projections around its periphery, flexible driving means engaging the tooth projections of said fixture plate, a movably mounted head member, a pressure roller revolvably mounted on said head member, a lever pivotally mounted on said head member, said lever being provided with a roller for engaging portions of said fixture plate, a second pressure roller revolvably mounted on said lever, fixture members mounted on said fixture plate, said fixture member engaging said second mentioned pressure roller, said fixture member being adapted to co-operate with said first mentioned pressure roller to bend the pipe, an arbor within the pipe, said arbor being provided with 35 a ball portion located adjacent said first mentioned pressure roller, means for supporting the outer end of said arbor, manually operated means for actuating said fixture plate to engage the roller of said lever, and manually operated means 40 for moving said movably mounted head member.

2. In a machine for bending a member, the combination of a movably mounted fixture member having an irregular shape, said fixture member being provided with tooth projections, said fixture member being provided with a pressure member for engaging the member to be bent, revolvably mounted members oppositely disposed about and respectively engaging the pressure member of said fixture member and the member 45 to be bent, and driving means engaging the tooth projections of said movably mounted fixture member.

3. In a machine for bending members, the combination of an arbor within the member to be bent, said arbor being provided with a spherical portion at its inner end, means for supporting said arbor at its outer end, and means for applying pressure against the outside of the member to be bent at points adjacent the spherical 50 surface of said portion of said arbor, said means com-

prising a fixture member suitably mounted to move about an axis and transversely relative to said axis.

4. In a machine for bending a member, the combination of means for supporting the member to be bent on an arbor, and means for bending the member, said means pulling the member off of said arbor during the bending operation, said means comprising a fixture member suitably mounted to move about an axis and in a plane extending transversely relative to said axis. 80

5. In a machine for bending members, the combination of means for applying pressure against the member to be bent, and a revolvably mounted fixture member engaging said means and the member to be bent, said revolvably mounted fixture member being provided with a plurality of irregular shaped portions for alternately engaging said means. 85

6. In a machine for bending members, the combination of pressure applying members, and a fixture member having portions traveling between said pressure applying members, said fixture member alternately traveling in a straight path and in a curved path. 90

7. In a machine for bending members, the combination of a movably mounted fixture plate, a fixture member mounted on said fixture plate, said fixture member being provided with sections movably connected relative to one another, a roller member suitably mounted on said fixture member, and a guide member suitably mounted, said guide member engaging said roller to cause said fixture member to be moved from its normal position to enable the machine to form a bend in the member to be bent. 105

8. In a machine for bending a member, the combination of a supporting member, a pair of sprocket members suitably mounted on said supporting member, a movably mounted fixture member, a chain member engaging said sprocket members and said fixture member, pressure applying members engaging said fixture member and the member to be bent, and means for driving said sprocket members. 115

9. In a machine for bending a member, the combination of a supporting member, a movably mounted fixture plate, revolvably mounted members between said supporting member and said fixture plate, pressure developing members, and a fixture member suitably mounted on said fixture plate, said fixture member having a portion engaging one of said pressure developing members together with the member to be bent. 125

10. In a machine for bending a member, the combination of a table, means for bending the member in the plane of said table, and means for bending the member along a line extending at an angle with the plane of said table, said last mentioned means bending said member after it has passed through said first mentioned means. 130

11. In a machine for bending a member, the combination of an arbor for supporting the member to be bent, said arbor extending within said member to be bent, means for supporting said arbor, and means for adjustably changing the position of said first mentioned means in longitudinal and transverse directions. 135

12. In a machine for bending a member, the combination of an arbor for supporting the member to be bent, and a member provided with open jaw portions for supporting said arbor, said arbor being supported between the open jaw portions of said last mentioned member to permit ready removal of said arbor therefrom. 140

13. In a machine for bending a member, the combination of an arbor for supporting the member to be bent, means for bending the member, said means pulling the member off of said arbor 80
- 5 during the bending operation, and means for anchoring said arbor to prevent longitudinal movement of said arbor, said second mentioned means comprising a member having an open portion adapted to receive said arbor therethrough 85
- 10 to permit ready insertion or removal of said arbor relative to said second mentioned means.
14. In a machine for bending a member, the combination of a movably mounted fixture plate having a rim portion extending peripherally 90
- 15 therearound, said rim portion having an equal overall width throughout its length, a roller suitably mounted, and means for causing said roller to engage the inside surface of said rim portion, and driving means engaging the rim portion of 95
- 20 said fixture plate.
15. In a machine for bending a member, the combination of pressure members located on opposite sides of the member to be bent, said pressure members constituting the sole means for 100
- 25 clamping said member during the bending operation and means for causing said pressure members to form the member to be bent.
16. In a machine for bending a member, the combination of pressure members, a fixture member 105
- 30 provided with movably mounted sections having means for limiting the movement of said sections beyond a pre-determined position, and means for moving said sections to allow said pressure members to form a bend in the member to 110
- 35 be bent.
17. In a machine for bending a member, the combination of a fixture member movably mounted and having a rim portion of substantially uniform width throughout its length, means for driving said fixture member, said means operatively 115
- 40 engaging said rim portion at one of its sides, means for resisting the thrust of said first mentioned means, said last mentioned means being oppositely disposed from said first mentioned 120
- 45 means relative to said rim portion, and means suitably mounted and cooperating with said fixture member to bend said member.
18. In a machine for bending a member, the combination of a fixture member, means suitably 125
- 50 mounted and cooperating with said fixture member to accomplish the bending, and means for actuating said fixture member to move about an axis during a portion of its movement, said fixture movement being actuated to move trans- 130
- 55 versely relative to said axis during a portion of its movement.
19. In a machine for bending a member, the combination of a fixture member movably mounted, said fixture member having a rim portion, 135
- 60 means suitably mounted and cooperating with said fixture member to accomplish the bending, driving means for actuating said fixture member, and means cooperating with said driving means to guide the rim portion of said fixture member 140
- 65 to travel around a plurality of axial points.
20. In a machine for bending a member, the combination of revolvably mounted means, a fixture member provided with a plurality of mem- 145
